UNITED STATES PATENT OFFICE.

JOSEPH C. WHITEHOUSE, OF COVINGTON, KENTUCKY.

SETTING FOR PRECIOUS STONES.

1,204,917.

Specification of Letters Patent. Patented Nov. 14, 1916.

Application filed May 24, 1915. Serial No. 30,011.

To all whom it may concern:

Be it known that I, JOSEPH C. WHITEHOUSE, a citizen of the United States, residing at Covington, in the county of Kenton and State of Kentucky, have invented 5 certain new and useful Improvements in Settings for Precious Stones, of which the following is a specification.

My invention consists in a novel setting 10 for precious stones whereby a cluster-plate having a number of small precious stones, such as diamonds, or other precious stones, set as a group or cluster therein, may be received in the setting and caused to closely 15 resemble a single deep large stone having a lower inverted pyramid.

My present invention is an improvement 20 upon the setting for precious stones shown, described and claimed in my application for Letters Patent of the United States Serial No. 5482, filed February 1, 1915.

The invention will be further readily understood from the following description and claims, and from the drawing, in which 25 latter:

Figure 1 is a side elevation of my improved setting, which may be a part of a scarf-pin, ring, or other piece of jewelry. Fig. 2 is a plan view of the same. Fig. 3 is a side elevation of a cluster-plate. Fig. 30 4 is a plan view of the same. Fig. 5 is an axial section of the cluster-plate showing the small stones therein, taken on a line corresponding to the line 5—5 of Fig. 4. Fig. 6 is a side elevation of my improved 35 setting, having the cluster-plate containing its precious stones, clamped in the setting. Fig. 7 is an axial section of the same, taken on the line 7—7 of Fig. 6. Fig. 8 is an 40 axial section of the same, taken on a line corresponding to the line 8—8 of Fig. 2.

The setting 11 comprises a series of setting-prongs 12. The setting-prongs diverge 45 from a common axis. There is a central space 13 within the series of setting-prongs, and a space 14 between the prongs of each pair of neighboring setting-prongs, these latter spaces preferably contracting toward 50 their lower ends.

Each of the setting-prongs is provided 55 adjacent its upper end with a shelf 16 above which a setting-claw 17 projects. 18 is a cluster-plate, the peripheral edge 19 of which is arranged to be received on the shelves 16 at the upper ends of the setting-prongs and to be clamped upon said shelves

by the setting-claws 17, the peripheral edge of the cluster-plate being received in the recesses 20 in the inner faces of said setting-prongs between said shelves and setting-claws.

Wires are arranged in the central space within the series of setting-prongs to resemble the lines of the boundaries of the facets of a brilliant below the girdle of a 60 precious stone and are secured in said space so as to have selective cluster-plates having small stones set therein selectively clamped in said outer setting above said wires to resemble a single large stone set in said setting. The set cluster-plates are preferably 65 releasable from said setting so that set cluster-plates may be removed and others substituted in the setting without disturbing 70 said wires. These wires are so arranged as to impart an appearance of depth in said resemblance to a single large 75 stone set in said setting. This is preferably accomplished by laterally diverging wires extending downwardly between said setting-prongs in said central space from a point below said cluster-plate. The resemblance 80 is enhanced by wires extending downwardly and inwardly into said central space and registering with the spaces between neighboring setting-prongs and extending upwardly toward said cluster-plate to a point 85 higher than the points to which said first-named downwardly laterally diverging 90 wires project upwardly.

The cluster-plate shown comprises a central flat top portion 26 and a downwardly slanting portion 27 surrounding said top portion, said top portion being provided with an axial bore 28 in which a small precious stone 29 is set, the slanting portion being provided with bores 30 surrounding said bore 28, in which bores 30 small precious stones 31 are set for forming a cluster 32 resembling the crown of a single large 100 stone, the central portion forming the table and the peripheral edge 19 of the cluster-plate forming the girdle.

The wires of the setting are located in the central space 13 within the series of setting-prongs and comprise wires 36 which slant downwardly and laterally from both sides of each of the setting-prongs from points 37 located in a plane at right angles to the axis of the setting below the plane at right 105 angles to said axis in which the shelves 16 are located, whereby said planes are spaced

apart by a space 38, said first-named plane being at a greater distance from the base of the setting than said second-named plane. The wires 36 which slant downwardly and laterally from both sides of each of the setting-prongs form angles 39 in said central space between the prongs of each pair of neighboring setting-prongs.

Diverging wires 42 diverge from a point 10 at or near the axis of the setting and extend radially upwardly and outwardly and intersect the angles 39 between the laterally downwardly diverging wires 36 and extend between the sides of said angles above the 15 meeting points of said laterally extending wires 36 and the setting-prongs, to a point adjacent to the lower face of the peripheral edge of the cluster-plate, but preferably spaced from said cluster-plate by a 20 slight space 43. The upper ends of the wires 42 are preferably free of attachment to the cluster-plate, whereby flexure of said upper ends of the wires 42 is permitted if desired.

25 The wires 36 and 42 are preferably fixed together in suitable manner and rigidly fixed within the space between the series of setting-prongs, preferably accomplished by fixing, as by brazing, soldering or similar 30 means, the upper ends of the wires 36 where they meet the setting-prongs to said setting-prongs, for fixing the wires in the setting. The wires 36 also act as spacing members for the wires 42.

35 The wires 36 diverge from the axis of the setting preferably at a different angle from the angle at which the diverging wires 42 diverge from said axis. The lateral wires 36 above their meeting points with the diverging wires 42 extend outwardly at a greater angle to the axis of the setting than do the wires 42, whereby said wires 36 are caused to meet the inner faces of the diverging setting-prongs 12 at points below 45 the plane at right angles to the axis of the setting in which the upper ends of the diverging wires 42 are located, these upper ends of the wires 42 preferably extending into the space between neighboring setting-prongs, so as to be located substantially in a circle having a diameter equal to the 50 diameter of a circle described from the axis of the setting in which the shelves 16 are located.

55 It will be noted that the upper ends of the wires in the setting closely resemble the under skew facets of a brilliant cutting of a precious stone, and the lower ends of the wires closely resemble the lower facets of the pavilion portion of a brilliant, the deep 60 positioning of the lateral wires 36 and their slightly greater outer inclination than the outer inclination of the wires 42 imparting the appearance of depth to the resemblance 65 to a single large stone set in the setting.

When therefore the cluster-plate, having the small precious stones set therein resembling the crown portion of a single large stone, is placed in the setting 11, above the wires therein, and the claws 17 of the setting-prongs are bent over the cluster-plate, the effect is a close resemblance to a deep single large precious stone in the setting, which is enhanced further by forming the wires out of a substance, for instance platinum, of a 70 different color from the color of the substance, for instance gold, out of which the setting 11 is formed.

Selective ones of the cluster-plates having small stones set therein to resemble the 80 crown portion of a single large stone are arranged to be received in the setting 11 above the wires, so that any one of numerous cluster-plates having different numbers or sizes of stones of different kinds therein can 85 be placed in any desired setting. Close resemblance to a single large deep-cut precious stone of brilliant cutting is produced by my improved device.

Having thus fully described my invention, what I claim as new and desire to secure by Letters Patent, is:

1. In a setting of the character described, the combination of a series of diverging setting-prongs having a space within said series, a framework of wires located in said space surrounded by said series of setting-prongs, said framework including wires slanting downwardly and laterally from both sides of said respective setting-prongs 100 and toward the axis of the setting and meeting and forming an angle between the prongs of each pair of neighboring setting-prongs to resemble the boundary lines of the under facets of the pavilion portion of 105 a single cut stone, the inner faces of said diverging setting-prongs provided with shelves located farther from the base of the setting than the upper ends of said framework of wires, and a cluster-plate for small 110 stones resting upon said shelves above and spaced from said framework of wires.

2. In a setting of the character described, the combination of a series of diverging setting-prongs having a central space within 115 said series, said setting-prongs provided with shelves, a framework of wires located in said central space, the planes perpendicular to the axis of the setting in which the upper ends of said wires and said shelves 120 are respectively located having a space between them, the wires of said framework extending inwardly and downwardly to resemble the boundary lines of the facets of the under portion of a cut precious stone, 125 said framework of wires fixed to said setting-prongs, and a cluster setting of small stones releasably received over and spaced from said wires and clamped in said setting on said shelves by said setting-prongs.

3. In a setting of the character described, the combination of a series of diverging setting-prongs the inner faces of which are provided with shelves adjacent to their upper ends, said series of diverging setting-prongs having a space within said series, the prongs of said series having open spaces between them, a framework of wires comprising a wire extending slantingly downward and inward from each side of each of said setting-prongs from points spaced from said shelves, said wires fixed to the setting-prongs from which they respectively extend, said wires meeting and forming angles between neighboring setting-prongs, diverging wires registering with said open spaces between the prongs and extending upwardly and outwardly and intersecting the apices of said angles and extending 20 above the plane at right angles to the setting in which said upper ends of said first-named wires are located, said first-named wires diverging from said axis at a greater angle than the angle at which said second-named wires diverge from said axis.
4. In a setting of the character described, the combination of a series of diverging setting-prongs having a space within said series, the prongs of said series having open spaces between them contracting toward their lower ends, the inner faces of said setting-prongs provided with shelves adjacent to their upper ends, a cluster-plate secured to said shelves, a framework of wires whose upper ends are spaced in a direction parallel to the axis of the setting from said shelves and cluster-plate, said framework including wires extending downwardly and laterally divergingly from both
- sides of said respective setting-prongs into 40 said first-named space so as to meet and form angles between said setting-prongs, and diverging wires intersecting the apices of said angles and registering with said open spaces and extending upwardly 45 higher than said upper ends of said first-named wires to points proximate to the peripheral edge of said cluster-plate but free of attachment thereto to resemble the boundary lines of the under facets of a single 50 stone.
5. In a setting of the character described, the combination of a series of diverging setting-prongs having a central space within 55 said series, the prongs of said series having open spaces between them, and a framework of wires received in said central space within said series of setting-prongs, said framework of wires comprising diverging wires and a wire extending upwardly and 60 outwardly from each side of each of said diverging wires to less height than the upper ends of said diverging wires, said second-named wires connected between each pair of diverging wires, said second-named 65 wires extending outwardly at a greater angle to the axis of the setting than the angle to said axis at which said first-named wires extend, and a cluster-plate for small stones 70 releasably received over said framework of wires within said series of setting-prongs.

In testimony whereof, I have hereunto signed my name in the presence of two subscribing witnesses.

J. C. WHITEHOUSE.
